YARN TENSION

David A. Tebo, Lawrence, Mass., assignor to
U S Bobbin & Shuttle Company, Manchester,
N. H., a corporation of Rhode Island

Application January 26, 1937, Serial No. 122,336

4 Claims. (Cl. 139—216)

This invention pertains to weaving shuttles and relates more particularly to shuttle tensions. While in certain of its aspects the present invention is of broader utility, it is especially valuable in association with yarn take-up devices such as are sometimes provided for taking up the slack in the yarn as the shuttle enters the box at one side or the other of the loom, thereby to avoid the interweaving of kinked yarn during the next 10 pick of the shuttle.

When such a take-up is used, it is essential to its effective operation, that the yarn acted upon by the take-up be that which extends from the shuttle toward the fell of the cloth. However, 15 unless a dependable restraining device be interposed between the bobbin and the take-up, the action of the take-up may be merely to draw off additional yarn from the bobbin, instead of applying tension to the yarn which extends out through the shuttle eye, thus defeating the purpose of the take-up. A principal object of the present invention is to provide effective means operative to prevent free withdrawal of yarn from the bobbin by the operation of the take-up.

Preferably, the means for preventing withdrawal of the yarn from the bobbin by the take-up is designed to restrain the yarn by friction rather than by a positive clamping action, and a further object is to provide such restraining means in the form of a tension device including friction pads between which the yarn passes and which act not only to prevent undesired withdrawal of yarn from the bobbin by the take-up, but also to apply the desired tension to the yarn 35 as the latter is drawn off from the bobbin during the flight of the shuttle.

In shuttles where a take-up is used, a large portion of the available space between the tip of the shuttle and the bobbin chamber must be reserved 40 for the reception and operative movement of the take-up parts, and thus any tension designed for use between the take-up and the bobbin must be of relatively small external dimensions. Accordingly a further object of the invention is to 45 provide a practical tension device effective for its intended purpose but at the same time of such small dimensions as to permit its installation in a normal commercial type of shuttle in which a take-up is also employed.

50 In weaving yarns of artificial silk or the like which are slippery and exceedingly wiry and prone to kink, great difficulty ordinarily is experienced in so controlling the yarn as to prevent the sloughing off of excess yarn from the tip of the bobbin and the delivery of kinked, knotted or

abnormally twisted yarn into the fell of the cloth, and a further object of the present invention is to provide a shuttle tension capable of applying such uniform and effective tension to the yarn even though of wiry, kinky character as to prevent excessive and kinked yarn from being delivered from the shuttle eye.

For use in weaving such a wiry yarn as artificial silk, flat or blade-like bobbins have recently come into use, said bobbins being wider transversely 10 than vertically as disposed in the shuttle chamber. Thus in leaving the bobbin tip, the yarn balloons in a horizontally elliptical path rather than in the usual circular path. In consequence, for most effective operation and to avoid excessive 15 wear, any tension employed for controlling yarn ballooning in this way should be so designed as to facilitate the approach of yarn thereto through a horizontal angle of substantial extent. A further object of the invention is to provide a 20 tension which may be disposed so as to be capable of receiving and tensioning yarn with substantially equal efficiency whether the yarn balloons in an elliptical path as when a flat bobbin is used, or balloons in a circular path resulting from the 25 employment of a bobbin of generally cylindrical shape.

Further objects of the invention are to provide a tension device which may readily be secured firmly in the shuttle body; to provide a tension 30 device which imposes substantially uniform tension on the yarn at all times; to provide a tension device having yarn-engaging parts which do not readily wear and which are not easily cut or scored by the running yarn, especially yarns 35 which are hard twisted, or of silk or artificial silk. A further object of the invention is to provide a yarn tension such that the tension applied to the yarn may readily be adjusted without removing the tension device as a whole from the 40 shuttle; and to provide a tension device of simple, durable and cheap construction which may be manufactured at low cost; which may readily be installed in the shuttle; and which has a useful life substantially as long as that of the shuttle 45 itself.

Other objects and advantages of the invention will be pointed out in the following more detailed description and by reference to the accompanying drawings, wherein

Fig. 1 is a plan view of a shuttle embodying the present invention;

Fig. 2 is a fragmentary side elevation of the shuttle of Fig. 1, drawn to larger scale, and

showing a take-up device installed within the forward end of the shuttle body;

Fig. 3 is a fragmentary horizontal section, to larger scale, substantially on the line 3—3 of Fig. 2;

Fig. 4 is a fragmentary vertical section substantially on the line 4—4 of Fig. 3;

Fig. 4^a is a section on the line 4^a—4^a of Fig. 3;

Fig. 5 is a rear elevation of the tension device 10 of Fig. 3 shown removed from the shuttle body;

Fig. 6 is an end elevation, partly in vertical section, of the tension device of Fig. 5;

Fig. 7 is a plan view of the tension device of Figs. 5 and 6;

Fig. 7^a is a perspective view, to large scale, of one of the yarn-tensioning friction pads;

Fig. 8 is a fragmentary longitudinal section through the forward part of the shuttle of Fig. 1, illustrating one desirable means of securing the 20 tension in place within the shuttle body;

Fig. 9 is a transverse section through a shuttle body at the forward end of the bobbin chamber, showing a shuttle eye such as that of Fig. 5 disposed with its longer axis vertical, and indicating 25 one desirable way of holding it in position;

Fig. 10 is a fragmentary plan view of a shuttle, partly in horizontal section, showing another mode of securing the tension device in position in the shuttle body;

Fig. 11 is a fragmentary plan view illustrating 30 a tension device of modified form embodying the present invention;

Fig. 12 is a fragmentary vertical section substantially on the line 12—12 of Fig. 11;

Fig. 13 is a rear elevation of the tension device 35 of Figs. 11 and 12 shown removed from the shuttle body;

Fig. 14 is an end elevation of the tension device of Fig. 13; and

Fig. 15 is a plan view of the tension device shown in Figs. 11 to 14 inclusive.

Referring to the drawings, the numeral 1 designates a weaving shuttle of conventional type, the shuttle having a bobbin chamber 2 provided at 45 its rear end with a bobbin-holding device 3 designed to hold a bobbin 4 in fixed position within the bobbin chamber. As illustrated in Figs. 1 and 3, the bobbin is a flat bobbin of the type which has been found highly desirable for use 50 with yarns of artificial silk or the like, the wider faces of the bobbin being normally disposed in substantially horizontal planes. The yarn Y forming the yarn mass 5 on the bobbin is (during the normal weaving operation) drawn off over 55 the tip of the bobbin, and is delivered from an eye or opening in the side of the shuttle at the forward end 6 of the latter. This forward end, as herein illustrated, is provided with a chamber or cavity 7 designed to receive a take-up device.

The take-up device, as here illustrated, comprises a length of wire bent to form an elongate take-up arm 8, and a portion coiled to embrace the pivot pin 9. This length of wire also comprises a portion 10 forming a short arm to which 60 is connected one end of a spring element 11, for example, a length of rubber elastic whose other end is anchored to the post 12, the normal tendency of the spring 11 being to swing the arm 8 toward the dotted position of Fig. 3. The arm 8 is furnished with a series of thread-engaging loops 13 which cooperate with interposed fixed posts 14 to draw the yarn into a zigzag path when the arm 8 is swung toward the dotted line position, thus tending to take up any slack in the 70 yarn. The yarn Y, after passing through the

loops 13, emerges from the side of the shuttle through an opening defined by fixed pins 16 and 17, the yarn bearing against one or the other of these pins in accordance with the direction of movement of the shuttle.

As shown in Fig. 4^a, the material forming the front wall 18 of the bobbin chamber is provided with an aperture or bore 19 leading from the bobbin chamber to the cavity or chamber 7 in which the take-up device is located. As illustrated in Fig. 4^a, this bore 19 is of more or less elliptical form with its longer axis substantially horizontal. This bore is designed to receive a yarn-restraining and tensioning device 20. This yarn-restraining and tensioning device, in accordance with the present invention, preferably comprises a block 20^a of any suitable material, such for example, as brass, bronze, aluminum, steel, porcelain or one of the synthetic resins (for example phenol-formaldehyde) and may be 15 shaped in any appropriate way, as by machining, die casting, moulding or the like. This block is externally dimensioned to fit snugly within the opening 19, if desired with a driving fit, so that no other retaining means may be necessary to 20 hold it firmly in place. The block is provided with a horizontal yarn passage extending from front to rear, and, as illustrated in Fig. 6, comprising the spaced parts 21 and 21^a. A transverse slot 22 intersects this yarn passage, the entrance end of the passage preferably being smoothly rounded or flared, as shown in 21^a, to provide an entrance throat. The exit end of the passage may likewise be flared and smoothly rounded, if desired. Preferably the throat 21^b 35 is substantially elliptical in contour (Fig. 5) with its major axis horizontal and substantially in the horizontal plane of the axis of the bobbin when the tension device is mounted within the shuttle.

Adjacent to the right and left-hand ends of 40 the yarn passage, posts 23 and 24, respectively, project upwardly from the bottom wall of the slot 22, the posts being fixed in the material of the block at their lower ends but having their upper ends free. These posts constitute guiding 45 and retaining means for a pair of yarn-engaging elements 26 and 32 designed to receive the yarn between them as it passes out from the bobbin chamber into the take-up chamber 7, and to apply frictional restraint to the yarn at a point 50 between the bobbin and the take-up. These restraining and tensioning elements are preferably disposed substantially horizontal, as shown in Figs. 4, 5 and 6, with their opposed yarn-contacting surfaces substantially in the horizontal plane 55 of the bobbin axis. Each of these elements preferably consists of a piece of sheet metal (Fig. 7^a) having a transversely elongate central part 27, the outer surface of which contacts with the yarn. The piece also comprises front and rear inclined 60 or beveled portions 28 and 29 designed to guide the yarn on its way to and from the outer surface of the part 27. Each of these elements or friction pads 26 and 32 is furnished with a pair of openings 30 and 31 adjacent to its opposite ends, 65 and when the pads are disposed within the slot 22 of the tensioning block, the pins 23 and 24 pass freely through these openings. The two tensioning and restraining pads 26 and 32 are substantially identical in shape and size, but are 70 so disposed within the slot 22 that the inclined or beveled edges of the two tension pads collectively form flaring guide throats 33 and 34 for directing the yarn into and out of contact with the substantially horizontal central portions of 75

the members 26 and 32. The tensioning and restraining pads 26 and 32 may be of any suitable material such, for example, as sheet steel which may be heat treated or otherwise hardened, or of 5 a wear-resistant alloy, or which may be of porcelain, glass or any other suitable material not readily cut or scored by the passing yarn. It may be noted that by the use of yarn-tensioning elements, which are elongate in the direction of 10 the major axis of the ellipse formed by the yarn as it balloons from the end of the flat bobbin, the yarn is permitted to move transversely from one side to the other of its general path of movement, that is to say, transversely of the front-to-rear 15 direction, so that the wear is distributed and so that, in fact, the moving yarn tends to polish the opposed surfaces of the tension elements rather than to cut definite grooves or channels therein.

Interposed between the under surface of the 20 member 26 and the bottom of the slot 22 are resilient cushioning elements such as coiled springs 26^a. These springs are conveniently arranged to embrace the posts 23 and 24, thereby holding the springs in proper position so that they 25 act at all times to cushion the lowermost pad 26, permitting the latter to yield downwardly either at one or both ends during use.

The material of the shuttle body immediately 30 above the location of the slot 22 is provided with a bore 35, (Fig. 4), in which is disposed a tension-adjusting screw 36 having an axial positioning nib which enters the upper part of a coiled tension spring 37, the lower end of which bears upon the upper surface of the tensioning pad 32 35 at a point substantially midway between the posts 23 and 24.

While it ordinarily suffices to press the tensioning block 20^a into position in the bore 19 of the shuttle body, it is contemplated that more positive retaining means may be provided if desired. 40 Thus, as illustrated in Fig. 8, the material of the shuttle body may be furnished with a bore 38 extending upwardly from the under side of the shuttle and which receives a set screw 39 whose upper 45 end bears against the under side of a block 20^a, thus furnishing additional means for retaining the block in position.

As illustrated in Fig. 9, it may be desirable 50 under some conditions, for example when a bobbin of the usual substantially cylindrical type is employed, to place the tension block 20^a with its longer axis vertical. In this event the bore in the wall 18 of the shuttle will be arranged with its longer axis vertical, and, after positioning the block 20^a in this bore, the block may be positively held in position, if necessary, by means of a set screw 40 disposed in a bore 41 leading inward from a side wall of the shuttle.

In Fig. 10 other means for holding the block 60 positively in position is shown. In this case the block 20^b is furnished with a pair of semi-cylindrical recesses at its opposite ends and these recesses receive pins 42 and 43 which are driven vertically down through the material of the shuttle body so as to engage the recesses in the block.

While the block shown in Figs. 4 and 7, inclusive, represents a preferred construction, it is contemplated that the tension block may be made in other ways within the scope of the invention. 70 For example, as illustrated in Figs. 11 to 15, inclusive, the tension device 20^c comprises a block 44 having the yarn passage 45 extending from front to rear and preferably of more or less elliptical transverse section with its major axis 75 horizontal and normally disposed substantially

in the plane of the bobbin axis. This yarn passage is furnished with a flaring entrance throat, but in this instance is intersected by a transverse slot 46 which opens at the rear edge of the block. Pins 47 and 48 pass through openings in the upper and lower walls of the slot 46, these pins being disposed adjacent to the ends of the major axis of the yarn passage and constituting guiding and retaining means for the yarn-tensioning and restraining members 50 and 51, which may be identical in shape and construction to the members 26 and 32 above described.

Coiled compressing springs 49 embrace the pins 47 and 48, respectively, and form cushioning supports for the lower tensioning member 50. In 15 this construction the upper wall of the slot 46 is furnished with an opening 52 substantially midway between the pins 47 and 48, and after the tension block has been mounted in the shuttle body (Fig. 12), a coiled tensioning spring 54 20 is dropped down through a suitable bore 55 in the material of the shuttle body and is then placed under compression by means of a tension-adjusting screw 56. For positively holding the block in position in the shuttle body, a set screw 25 57 may be arranged to pass down through the material of the shuttle and to engage the upper surface of the block 44.

In the operation of the device, for example as 30 illustrated in Figs. 1 to 8, the yarn Y is drawn off from the yarn mass 5 on the bobbin and is first threaded between the tensioning members 26 and 32 (by means of a suitable hook or needle) and through the several loops 13 of the take-up device, and then passes out through the shuttle 35 eye defined by the fixed pins 16 and 17. By turning the tensioning screw 36, the pressure exerted by the spring 37 upon the upper tensioning member 32, may be so adjusted as to provide the desired frictional pressure upon the yarn 40 during the weaving operation. By cushioning the tension member 26 upon the laterally spaced springs 26^a, and by applying the tensioning pressure by means of a centrally disposed single spring 37, a very uniform tension is secured. As 45 already noted, the approaching yarn, although its angle of approach varies very substantially in unwinding from the flat bobbin, is always free to move through the yarn passage (without encountering any deflecting obstacle) by reason 50 of the transversely elongate shape of the tensioning elements, and thus there is no tendency to crimp the yarn or cause variations in tension as the yarn pulls off from the bobbin. Furthermore, by reason of the cushioning of both of the tension-applying members 26 and 32, their opposed 55 yarn-engaging surfaces may rock transversely in unison, maintaining their substantially parallel relation at all times, and in this way tend 60 to maintain uniformity of tension and at the same time gently to grip and smooth the yarn and then to straighten out knots or kinks which approach the tensioning device. In fact this tensioning device is highly effective in preventing 65 the passage of abnormal twists or kinks from the bobbin chamber to the take-up chamber. By the use of yarn-engaging tensioning surfaces of the substantial extent afforded by the device here illustrated, it is possible to restrain the yarn and 70 apply tension thereto by the use of a relatively gentle pressure of the spring 37. This spring is so adjusted that when the take-up arm acts as the shuttle enters the box at one side or the other of the loom, the yarn is held back by the 75

tension device so that all of the slack which is then taken up by the take-up device is that which extends from the exit end of the tension toward the fell of the cloth. This provides for a satisfactory operation of the take-up such as can not be secured unless restraining means be interposed between the take-up and the bobbin.

In the tension device of Figs. 4 to 7 inclusive, the tensioning elements 26 and 32 may be removed from the block after the latter has been withdrawn from the shuttle body merely by lifting them from off the pins 23 and 24, thus permitting the ready replacement of these tensioning members, if worn. On the other hand, to remove the tensioning members 50 and 51 from the block 44 of Figs. 12 to 15, it is necessary first to remove the pins 47 and 48. However, these pins need not be fixed within the block, since, after the block has been installed in the body of the shuttle, these pins can not escape even though seated within the block with a sliding fit.

While certain desirable embodiments of the invention have herein been illustrated by way of example, it is to be understood that the invention is not to be limited to these precise constructions but is to be regarded as inclusive of all equivalents falling within the scope of the appended claims.

I claim:

30 1. A shuttle of the kind having therein a bobbin chamber and a take-up chamber separated from the bobbin chamber by a transverse wall, said wall having therein an aperture disposed wholly below the top surface of the shuttle, characterized in having a tension device comprising a block fitting snugly within said aperture and having a recess at one, at least, of its ends, and a retaining element fixed within the shuttle body and entering said recess thereby positively to hold the block in operative position, and tension elements housed within the block.

45 2. A shuttle of the kind having therein a bobbin chamber, a second chamber separated from the bobbin chamber by a transverse wall, and a tension device comprising a housing set in an aperture in said wall, characterized in that said aperture is of substantially elliptical contour in transverse vertical section with its longer axis substantially horizontal, the housing being of such external shape and dimensions as to fit snugly within said aperture and having a yarn passage leading from one chamber to the other, said passage being provided with a substantially elliptical entrance throat, and a pair of yarn-

engaging pads disposed within the housing, said pads being elongate widthwise of the shuttle.

3. A shuttle of the kind having therein a bobbin chamber and a take-up chamber separated from the bobbin chamber by a transverse wall, and means within the bobbin chamber for holding a flat bobbin with its wider faces substantially horizontal, characterized in having a tension block fixed in an aperture in said transverse wall, the block having a transversely elongate yarn passage disposed substantially in the plane of the tip portion of a flat bobbin mounted in the bobbin chamber, a pair of friction pads housed within the block, said pads having opposed yarn-engaging surfaces normally disposed substantially in the horizontal plane of the axis of the bobbin, said pads being elongate widthwise of the shuttle thereby to permit free transverse deviation of the yarn as it approaches the tensioning device in ballooning from the tip of the bobbin, guide means engaging the pads at transversely spaced points, said guide means being so designed and arranged as to permit the two pads to tilt laterally in unison in either direction, resilient cushioning means engaging 25 the outer surface of one pad adjacent to its opposite ends respectively, and a tension-applying spring engaging the outer surface of the other pad substantially midway between its ends.

4. A shuttle of the kind having therein a bobbin chamber and a second chamber separated from the bobbin chamber by a transverse wall, the latter having an aperture connecting the two chambers, and means within the bobbin chamber for holding a flat bobbin with its wider faces substantially horizontal, characterized in having a tension block fixed in the aperture in said transverse wall, the block having a transversely elongate yarn passage, a pair of friction pads housed within the block, said pads having opposed yarn-engaging surfaces normally disposed substantially in the horizontal plane of the axis of the bobbin, said pads being elongate transversely of the shuttle thereby to permit free transverse deviation of the yarn as it approaches the tensioning device in ballooning from the tip of the bobbin, means operative to hold the pads in registering relation while permitting them freely to move toward and from each other, resilient cushioning means for one of the pads, a tension-applying spring engaging the other pad, and means accessible from the exterior of the shuttle for varying the tension force applied by said spring.

DAVID A. TEBO.
